UNITED STATES PATENT OFFICE.

EDWARD C. SHANKLAND, OF CHICAGO, ILLINOIS, ASSIGNOR TO D. H. BURNHAM & CO., OF SAME PLACE.

SAFE OR VAULT.

SPECIFICATION forming part of Letters Patent No. 615,503, dated December 6, 1898.

Application filed November 30, 1897. Serial No. 660,273. (No model.)

To all whom it may concern:

Be it known that I, EDWARD C. SHANKLAND, a citizen of the United States, residing in Chicago, county of Cook, and State of Illinois, 5 have invented certain new and useful Improvements in Safety-Vault Construction, of which the following is a specification.

My present invention, the subject-matter of which was originally a part of an application on safety-deposit vaults filed by me July 16, 1897, Serial No. 644,852, patented January 18, 1898, No. 597,694, has relation to improvements analogous to those disclosed in the remaining portion of the application referred to.

The primary object is to prevent or retard entrance by criminals into safety - deposit vaults through the instrumentality of an electric arc. The destructive action of this 20 means of attack is of comparatively recent development and requires radical improvements for its successful resistance.

In the application before mentioned I have already explained somewhat at length the 25 conditions and difficulties referred to, together with one form of construction which to me seemed well adapted to meet the present requirements of the art.

By my present invention I aim to secure as 30 good or better results than those obtained from the prior construction referred to by means of still further improvements.

In conjunction with my present construction (although as to this other forms of construction could be used, if desired, without departing from the spirit of this invention) I 35 preferably employ the invention of the application mentioned, building up the framework of the vault out of a plurality of wall 40 layers, each composed of parallel rails embedded in concrete or other material of low conductivity. Between the wall layers so formed I propose in the preferred construction of my present invention to provide a 45 separate interfilling layer of high electrical-resistance material and to embed therein a plurality of inserts or broken sections, inserts, or pieces of metal so disposed as to be entirely insulated not only from the surrounding metal 50 lining of the inclosing space, but also from each other. These broken rods, inserts, or

filling-pieces of metal being thus insulated renders it necessary in order to burn them by the electric current that a hole leading into them should be made sufficiently large 55 to accommodate not only the destroying-tool, but also a ground or return wire, (which is scarcely practical in view of the intensity of the heat of the arc,) or else that two holes should be made leading into the same rod or 60 piece of filling material, one of which can be used for a ground-wire and the other for the insertion of the device employed to form the arc.

The exact location and arrangement of the 65 inserts or rods it is of course impossible to determine from the outside, especially if they be of varying length and shape. Hence in making a second hole there is much greater chance that some other rod will be encountered rather than the one first struck, which of course necessitates still another hole, and so on until the proper broken piece or section of rod is found.

A further object of my invention is to secure a more efficient protection for the door and the lock, the latter being recognized as one of the most vulnerable points in safe construction. To attain this end, I provide in the center of the door a space or inclosing 75 chamber, which I fill with some material of high electrical resistance and in which, as in the construction of the walls, I embed a number of broken rods or pieces of metal so disposed as to be thoroughly insulated.

In the practice of my invention it is preferable to use some form of concrete as a filling material and to embed therein short or broken pieces of steel rods arranged in a double row or layer and in staggered position 80 relative to each other, for by such means the maximum degree of efficiency is secured.

I will now proceed to describe my invention in connection with the accompanying drawings, in which—

Figure 1 is a horizontal section through the corner of a safety-deposit vault built in accordance with my invention. Fig. 2 is a vertical section through an upper corner of the vault. Fig. 3 is a horizontal section showing 95 a portion of one corner with the door in place, and Fig. 4 is a detail illustrating the preferred

arrangement of the rows or layers of broken pieces.

Referring now more particularly to Figs. 1 and 2, it will be seen that I have provided an outer layer of rails and concrete 5 and an inner layer of rails and concrete 6 and that between a plate 7 and the flanges 8 of the rails of the layer 5 is an inclosing space filled with a concrete layer 9. In this concrete layer is embedded a plurality of broken or short rods 10, of steel, arranged with their ends separated and also separated from the metal walls of the inclosing space and from each other by the concrete filling. If an attempt be made to penetrate this protection by means of an electric arc, it is obvious that before any one of the filling-pieces or short rods can be fused or burned the electrical circuit must be in some manner completed through it by means 20 of a ground or return wire. If by burning and chipping a hole be made from the outside into one of the outer ones of the insulated rods, as at 11, serious difficulty will be encountered in proceeding further, because the 25 rod being of metal or steel of great hardness it cannot be easily attacked by means of tools or drills, and the electric arc has no effect upon it until it can be connected in some manner with a ground or return wire. Unless 30 the hole first made were excessively large it would be of course impossible to secure such ground or return for the current through the same opening. Hence to get such attachment before further progress can be made a second 35 hole would have to be made, and if this failed (as the chances are it would) to reach the same rod as was encountered in making the first hole, as at 12, still others would be necessary until a means for returning the 40 current is secured and the ground-wire attached through it. All this of course represents additional delay, with embarrassment on the part of the criminal, and increases by so much the probability of his burlarious attempt being frustrated.

Referring now to Fig. 3, attention is called to the method I have shown for securing protection of the door 13 and the lock 14. In the door is formed the inclosing space 15, in which 45 is placed an interfilling material of high electrical resistance, 16, having embedded therein a number of the broken rods or pieces 10 before referred to. By placing the lock immediately back of the center of the door, as 50 shown, and providing in front of it the large chamber in the door, protected as described, I make it a matter of extreme difficulty to reach the lock from the outside, and so hinder any attempted entrance through this place.

While I have especially described the use 55 of concrete or a similar material with the rods or inserts embedded therein as a means of insulating said inserts, still it is obvious that they could be insulated in other ways, if preferred, and without the use of any filling material.

Having thus described my invention, what

I claim as new, and desire to secure by Letters Patent, is—

1. A wall for vaults, safes, &c., comprising a supporting structure or frame, tool-resisting metallic inserts sections or pieces of varying dimensions and insulating material whereby said inserts sections or pieces are held so as to be electrically insulated from said frame and from each other, substantially as described. 70

2. A wall for vaults, safes, &c., comprising a supporting structure or frame containing tool - resisting metallic inserts sections or pieces embedded in concrete, and so disposed as to be electrically insulated from said frame and from each other, substantially as described. 80

3. A wall for vaults, safes, &c., comprising a supporting structure or frame containing tool - resisting metallic inserts sections or pieces of varying dimensions embedded in a material of high electrical resistance, and so disposed as to be electrically insulated from said frame and from each other, substantially as described. 90

4. A wall for vaults, safes, &c., comprising two layers of rails in combination with a plurality of insulated metallic inserts sections or pieces, substantially as described. 95

5. A wall for vaults, safes, &c., comprising a plurality of layers composed of rails in combination with a plurality of insulated metallic inserts sections or pieces between said layers, substantially as described. 100

6. A wall for vaults, safes, &c., comprising a plurality of layers composed of rails embedded in concrete in combination with insulated metallic inserts sections or pieces, substantially as described. 105

7. A wall for vaults, safes, &c., comprising a plurality of layers composed of rails, the rails of adjacent layers crossing each other, embedded in concrete in combination with insulated metallic inserts sections or pieces, substantially as described. 110

8. A wall for vaults, safes, &c., comprising a plurality of layers composed of rails, the rails of adjacent layers crossing each other, in combination with insulated metallic inserts sections or pieces, substantially as described. 115

9. In safety-vault construction the combination with a door and a lock located inside of the center of said door, of an inclosing space in the door in front of said lock, an interfilling material of high electrical resistance in said inclosing space, and a plurality of broken pieces of tool-resisting metal embedded in said interfilling material, and so arranged as to be electrically insulated not only from the surrounding metal of the inclosing space, but also from each other, substantially as described. 120

10. In safety-vault construction the combination with a door and a lock located inside of the center of said door, of an inclosing space in the door in front of said lock, an in- 125

terfilling material of high electrical resistance in said inclosing space, and a plurality of steel rods embedded in said interfilling material, and so arranged as to be electrically insulated not only from the surrounding lining of the inclosing space, but also from each other, substantially as described.

5 11. A wall for vaults, safes, &c., comprising a supporting structure or frame, tool-resist-

ing metallic rods of varying dimensions, and insulating material whereby said rods are held so as to be electrically insulated from said frame and from each other, substantially as described.
